1948, Serial No. 57,876

16 Claims. (Cl. 62—5)

1

My invention relates to refrigeration and particularly to control devices for domestic refrigerators. More particularly, my invention relates to "defrosting" controls for domestic refrigerators of the unipressure absorption type.

This application is a continuation of and relates back for common subject matter to my earlier application Serial No. 591,753, filed May 3, 1945, now abandoned.

In domestic refrigerators provided with a low temperature evaporator or cooling element for freezing ice cubes and a high temperature evaporator for cooling the food storage compartment, it is necessary to operate the low temperature evaporator at a temperature well below the freezing point of water and, due to the presence of water vapor in the air which comes in contact with this low temperature evaporator, moisture condenses and congeals on the surface of the low temperature evaporator. This congealed moisture produces a layer of frost or ice which gradually accumulates and decreases the efficiency of the refrigerator. This accumulated frost is undesirable also from the standpoint of sanitation. The high temperature evaporator, on the other hand, operates at a temperature above the freezing point of water; therefore, moisture does not congeal on the high temperature evaporator.

With the type of refrigerators above referred to, it is desirable that the low temperature evaporator be "defrosted" without interfering with the normal operation of the high temperature evaporator. Also, since the rate of accumulation of frost on the low temperature evaporator varies under different conditions of operation, and since it is not always convenient to interrupt operation of the low temperature evaporator in order that it may be defrosted, it is desirable that defrosting may be started voluntarily. However, it is desirable that the refrigerator be automatically returned to normal operation after the frost or ice has been removed from the low temperature evaporator.

I have invented a control for a refrigerator having a plurality of compartments maintained at distinctly different temperatures. This control includes mechanism whereby an evaporator for cooling one of the compartments may be defrosted while refrigeration is continuously produced by another evaporator for maintaining another of the compartments at substantially constant temperature. This control also includes means whereby the defrosting cycle of one evaporator is manually initiated and automatically stopped responsive to the temperature of said one

2

evaporator without interrupting the production of refrigeration by another evaporator. This control further includes an arrangement whereby a single conveniently-located dial is utilized for manually initiating a defrosting cycle for one evaporator and for adjusting the temperature at which another evaporator shall operate.

These and other objects and advantages of my invention will be apparent from the following description taken in connection with the accompanying drawings, wherein like reference numerals are used to designate like parts throughout the different views, and wherein:

Fig. 1 illustrates more or less diagrammatically 15 a refrigerating system incorporating my improved control;

Fig. 2 is a broken view in front elevation of a refrigerator, partly in section, showing the cooling elements and a dual control incorporating 20 my invention;

Fig. 3 is a side view, partly in vertical section, of the arrangement illustrated in Fig. 2;

Fig. 4 is an enlarged horizontal sectional view 25 of a part of the control device illustrated in Figs. 2 and 3;

Fig. 5 is a front view of the housing of the control device illustrated in Fig. 4.

Referring particularly to Fig. 1 of the drawing, there is illustrated an absorption refrigerating system of the unipressure type provided with a rapid defrosting device with which my improved dual control is adapted to be incorporated. This particular refrigerating system is not my invention, but is the invention of Benjamin A. Phillips and is described and claimed 30 in his copending application Serial No. 591,609, filed May 2, 1945. This system includes a generator 10, a rectifier 11, a condenser 12, an evaporator 13, a gas heat exchanger 14, an absorber 15 and a liquid heat exchanger 16 all interconnected in a manner well known in the art which will be described more in detail hereinafter. The system is charged with a solution of refrigerant and absorption liquid, and with a pressure-equalizing gas which is inert with respect to the refrigerant and absorption liquid. It is preferred to use ammonia as the refrigerant, water as the absorbent, and hydrogen as the inert pressure-equalizing gas.

50 The cooling element or evaporator 13 includes an upper or low temperature section 13a located in a freezing compartment 18 of a thermally-insulated refrigerator cabinet 20 and a lower or high temperature section 13b located in a food storage compartment 22 of the refrigerator cab-

inert. Evaporator sections 13a and 13b are connected for series flow of refrigerant fluid and inert gas by a conduit 13c. Freezing compartment 18 and storage compartment 22 are separated by a thermal insulating panel 24. Evaporator section 13a is provided with a plurality of dams 26, only two of which are shown, for accumulating liquid refrigerant in said section. Evaporator section 13b is provided with heat transfer fins 28. Liquid refrigerant flows from condenser 12 through conduits 30 and 32 into the upper portion of low temperature section 13a of the evaporator where it evaporates and diffuses into weak inert gas flowing into said evaporator section through a conduit 34 connected to gas heat exchanger 14, thereby producing a desired refrigerating effect. The enriched inert gas along with liquid refrigerant flows from low temperature section 13a through conduit 13c to high temperature section 13b where additional refrigerant vaporizes and diffuses into the inert gas producing additional refrigeration, but at a higher temperature. The resulting gas mixture of refrigerant and inert gas flows from evaporator section 13b through a conduit 36, inner passage 38 of gas heat exchanger 14, a conduit 40 and a vessel 41 into the lower portion of absorber 15.

In absorber 15 refrigerant vapor is absorbed by absorption liquid which enters the upper portion of the absorber through a conduit 42. The inert gas stripped of refrigerant vapor flows from the upper portion of the absorber, through outer passage 44 of gas heat exchanger 14 and conduit 34 back to low temperature evaporator section 13a to complete the inert gas circuit. The circulation of inert gas between the evaporator and absorber is due to the difference in specific weight of the column of inert gas rich in refrigerant flowing from evaporator section 13b to the absorber and the column weak in refrigerant vapor flowing from the absorber to evaporator section 13a. The column of inert gas rich in refrigerant vapor being heavier than that weak in refrigerant, a force is produced which causes circulation of inert gas through and between the evaporator sections and the absorber.

Absorption liquid enriched in refrigerant flows from the lower portion of absorber 15 into and through vessel 41, through a conduit 46, inner passage 48 of liquid heat exchanger 16 and a vapor lift pump 50 into generator 10. A flue 52 extends axially and concentrically through generator 10, and is arranged to be heated by any suitable means such, for example, as a gas burner 54. As shown, the lower portion of vapor lift pump 50 is coiled about and is in intimate heat exchange relation with the lower portion of flue 52. Refrigerant vapor is expelled from the refrigerant-absorbent solution in generator 10 due to heating by burner 54, and this vapor together with vapor entering through vapor lift pump 50, flows through rectifier 11, a conduit 56 and a liquid trap 58 into the upper portion of condenser 12. In passing through the rectifier any water vapor which may have been expelled from the generator with the refrigerant vapor is condensed and flows back to the generator. The refrigerant vapor is condensed and flows back to the generator. The refrigerant vapor is condensed in condenser 12 and the liquefied refrigerant is returned to the upper evaporator section through conduits 30 and 32 to complete the refrigerant circuit.

The absorption liquid which has been weakened by expulsion of refrigerant therefrom flows from the lower portion of generator 10 through a

conduit 60, outer passage 62 of liquid heat exchanger 16 and conduit 42 back to the upper portion of absorber 15 completing the absorption liquid circuit. The circulation of absorption liquid results from raising liquid into the generator by vapor lift action through pump 50. The heat produced in the absorber by the absorption of refrigerant vapor into absorption liquid may be transferred from the absorber by any suitable means such, for example, as by air-cooled heat transfer fins 64.

The outlet end of condenser 12 is connected by a conduit 66, a pressure vessel 68 and a conduit 70 to a part of the inert gas circuit, as at the upper end of gas heat exchanger 14, for example, so that any inert gas which passes through the condenser may flow back to the gas circuit. Refrigerant vapor not liquefied in the condenser flows through conduit 66 and into vessel 68, displacing inert gas therefrom and forcing said gas through conduit 70 into the gas circuit. In this manner, the total pressure in the entire system is increased to insure continuous refrigeration. The supply of fuel gas to burner 54 is controlled by a thermostatically-operated valve 94 to be described in more detail hereinafter.

In order to rapidly defrost low temperature evaporator 13a, the refrigerant vapor is by-passed around the condenser and conveyed directly from the rectifier to the low temperature evaporator. For this purpose, a conduit 72 is connected at one end to conduit 56 and at its opposite end to conduit 34 leading to the inlet end of evaporator section 13a. Conduit 72 is formed with a U-shaped portion to provide a liquid trap 74. In order to retard or stop the flow of weak inert gas into evaporator section 13a during a defrosting period, a by-pass is provided in the inert gas circuit. This by-pass includes a conduit 76 connected at one end to conduit 34 and at its opposite end to conduit 13c which leads from the low to the high temperature evaporator section. Conduit 76 is formed with a U-shaped portion to provide a liquid trap 78. In practice, conduits 34 and 76 and gas heat exchanger 14 are provided with suitable thermal insulation (not shown). Trap 78 is connected to trap 74 by means of a conduit 80. Liquid in trap 74 is arranged to be heated by any suitable means, such for example as an electric heating element 82. Heating element 82 is connected to a suitable source of electrical energy, as a house line, by means of conductors 84 and 86. As shown, a switch 88, which will be described more in detail hereinafter, is located in conductor 84 for energizing and deenergizing heating element 82. A thermal bulb 90, positioned in heat exchange relation with low temperature evaporator section 13a and connected to switch 88 by a capillary tube 92, controls the deenergization of the heating element.

Referring now to Figs. 2 and 3, the apparatus illustrated in Fig. 1 is mounted in the cabinet 20 with the low temperature evaporator 13a located in freezing compartment 18, the high temperature evaporator 13b located in food storage compartment 22 and a generator 10' located principally in an apparatus compartment 100. The other parts of the apparatus are located either in apparatus compartment 100 or in a vertical passage 101 at the rear of the cabinet. Gas is supplied to the burner 54 from a supply conduit 102 and control device 94. It is to be noted that the generator 10' partly illustrated in Fig. 3 is a well known horizontal type of generator, while the generator 10 illustrated in Fig. 1 is a well known vertical type gen-

erator. As stated above, the refrigerating system per se is not a part of my invention and the use of a horizontal generator in Fig. 3 is merely for convenience in illustrating the relationship of my control device to a generator. The patent to Ullstrand No. 2,252,791, granted August 19, 1941, for example, illustrates and describes a well known type of horizontal generator, portions of which I have illustrated in Fig. 3.

The control device 94, shown in detail in Fig. 4, 10 comprises an annular casing or housing consisting of an annular body member 103, a front cover plate 104, and a rear cover plate 105, the cover plates being secured to the body member by suitable machine screws (not shown). The interior of body member 103 is divided by a partition 106 having a central boss 107 through which is drilled a valve opening 108. Extending through the valve opening is a valve stem 109 provided at one end with a valve member 110 in a valve chamber 111. The boss 107 is machined to form a seat for valve member 110 so that the latter may control flow of gas through the valve opening 108. The valve member is biased to its closed position by a suitable coil spring 112. In a valve chamber 113 on the other side of the partition 106 there is located an expansible diaphragm 114 of an expansible fluid thermostat. Expansible diaphragm 114 is mounted on a resilient diaphragm 115 which is secured at its edge with a suitable gasket between body member 103 and front cover member 104, thus sealing the valve chamber 113. Expansible diaphragm 114 is connected by a capillary tube 97 to a sensitive bulb 96 located in thermal transfer relation with the high temperature evaporator 13b, as shown in Figs. 1-3. The sensitive bulb 96, capillary tube 97 and expansible diaphragm 114 are charged with a suitable temperature sensitive fluid as well known in the art. As shown, expansible diaphragm 114 is located in operative relation with the valve stem 109, whereby movement of the expansible diaphragm responsive to variation in temperature of the high temperature evaporator 13b is transmitted by valve stem 109 to valve member 110 to control the flow of fuel gas through valve passage 108. Body member 103 is provided with an external boss 116 drilled for passage of gas therethrough into valve chamber 113 and tapped for a gas pipe connection to supply conduit 102. A second external boss 117 is drilled for passage of gas from the other valve chamber 111 and is tapped for a gas pipe connection to the burner 54. Thus, the supply of gas to burner 54 is controlled by valve member 110 which is operated by the expansible diaphragm 114 in accordance with the temperature of the high temperature evaporator 13b.

In order to provide a minimum flow of gas to burner 54 to maintain a pilot flame when valve 110 is closed, there is provided a by-pass conduit from valve chamber 113 comprising passages 150, 151, 152 and 153, as best seen in Fig. 5. The by-passed flow of gas from passage 151 into passage 152 is adjusted by a screw type needle valve (Fig. 2). Burner 54 is provided with a thermostatic safety cut-out valve 155, of a type well known in the art, and with a burner lighter tube 156 controlled by a normally-closed manually-operated push valve 157. As shown in Fig. 5, gas is admitted to the lighter valve through a passage 158 from valve chamber 113.

As shown, the control device 94 is positioned in the apparatus compartment of the refrigerator cabinet, which position renders the control somewhat inaccessible, or at least inconvenient, to ad-

just. Therefore, I provide a remotely-operated adjustment generally similar to that illustrated and described in my U. S. Patent No. 2,123,920, granted July 19, 1938. Referring again more particularly to Fig. 4, there is provided in the outer cover plate 104 an insert bushing 118 which is internally threaded to receive an adjusting screw 119 provided with a rounded portion 120 on its inner end and an octagonal head 121 on its outer end. The outer end of screw 119 is drilled and tapped to receive a machine screw 122. The rounded inner end of screw 119 forms an abutment for a member 124. Member 124 projects centrally through the resilient diaphragm 115 and is secured thereto by a retaining nut 125, thus forming a means by which the expansible diaphragm 114 is mounted on resilient diaphragm 115 and also a means by which capillary tube 97 is connected to expansible diaphragm 114; a passage 126 through the element 124 serves this purpose. A grooved pulley 127 formed with an octagonal recess, is mounted on the octagonal head of adjusting screw 119 and secured thereto by machine screw 122. Rotation of the pulley moves adjusting screw 119 toward or away from member 124, thereby varying the position of member 124 to effect an adjustment or setting of thermostatically-operated valve 110. Suitable stops (not shown) may be provided for limiting inward and outward movement of adjusting screw 119.

Referring again to Figs. 2 and 3, an adjusting knob 129 provided with a fixed dial or index plate 130, is mounted on the end of a rod 131 which extends from the front of the low temperature compartment 18 through the rear wall of said compartment into the vertical passage 101 where it is provided with a grooved pulley 132 similar to pulley 127 on control device 94. The two pulleys are operatively connected by a flexible wire belt 133 provided with a guide casing 134. Turning the knob 129 causes rotation of rod 131, pulley 132, and pulley 127, whereby the adjustment of the control thermostat is varied as previously described. Dial 130 is provided with suitable stops 130a and 130b which respectively prevent counter-clockwise rotation of knob 129 beyond the point A and clockwise rotation beyond the point M.

In accordance with my invention, switch 88, 50 previously referred to for energizing and deenergizing heating element 82, is manually operated to initiate a defrosting cycle and thermostatically operated responsive to the temperature of the low temperature evaporator 13a for stopping the defrosting cycle and resuming normal operation of the refrigerating apparatus. As shown particularly in Fig. 2, switch 88 comprises a housing or supporting member 135 suitably mounted adjacent control device 94 in the apparatus compartment 100. A cover plate 136 is mounted on housing 135, as by screws (not shown), and clamps or secures the edge of a resilient diaphragm 137 to the housing. An expansible diaphragm 138 is centrally mounted on resilient diaphragm 137 by means of a member 139 which is generally similar to member 124 of control device 94. Member 139 is provided with a passage (not shown) by which capillary tube 92 is connected to expansible diaphragm 138. The sensitive bulb 90, located in thermal transfer relation with low temperature evaporator 13a, capillary tube 92 and expansible diaphragm 138, are charged with a temperature-sensitive fluid and together form a fluid thermostat. An abutment pin 140, mounted centrally on one side of expansible diaphragm

138, operates a switch lever 141 which is pivotally mounted on housing 135. The switch lever is bifurcated at its lower end and adapted to loosely engage a knob 142 connected to an electric switch 142'. Switch 142' which may be of any suitable type, is arranged in the conductor 84 for opening and closing the circuit to the electric heating element 82. A flexible push rod 143 is mounted for reciprocating movement in a bracket 144 and is provided at one end with an abutment pin 145 adapted to contact switch lever 141. The opposite end of rod 143 is positioned adjacent the outer face of pulley 127 attached to control device 94 so that a boss 146 formed on said pulley moves the push rod to the right when said pulley is rotated clockwise to the position shown in Fig. 2, whereby abutment pin 145 contacts and moves lever 141 and switch button 142 to the right to close switch 142' and energize heating element 82. Push rod 143 is biased toward boss 146 by a suitable tension spring (not shown). Cover plate 136 is drilled and tapped to receive an adjusting screw 147. Screw 147 is adjusted at the factory and held in fixed position by a set screw 150. Adjusting screw 147 is formed with a passage to receive a shaft 148 on a reset button 149. The arrangement is such that movement of the reset button to the left, as viewed in Fig. 2, manually resets the switch 142'. By this arrangement, defrosting may be interrupted if it has been started inadvertently or at an inopportune time.

In operation, assume that the refrigerating system has been operating normally for a period of time and that frost or ice has accumulated on the low temperature evaporator 13a and should be removed; in other words, evaporator 13a should be defrosted. For rapid defrosting and automatic return to normal operation, control knob 129 is rotated counter-clockwise to the position shown in Fig. 2; that is, to the position where the pointer on the knob registers with the mark A on dial 130. Rotation of knob 129 to this position causes the pulley 127 of control device 94 to rotate clockwise to the position shown in Fig. 2, whereby the boss 146 on pulley 127 will have contacted and moved push rod 143 to the right causing the switch lever 141 to move switch button 142 to close switch 142', thereby energizing heating element 82. After the knob has been rotated to this defrosting position, it is immediately returned to the desired or former setting which causes thermostatic valve 110 to continue to supply gas to burner 54 and refrigerant vapor to continue to be generated by generator 10 in accordance with the demands of high temperature evaporator 13b. Turning knob 129 clockwise to the point marked M would cause the burner to remain on by-pass or pilot flame as long as the knob remains in this position for slow manual defrosting.

Referring again more particularly to Fig. 1, the energization of heating element 82 causes the liquid in trap 74 to be heated, whereby the liquid is vaporized and removed from the trap. The removal of liquid from trap 74 may be effected entirely by vaporization of the liquid or by vapor liquid lift action. It is preferred to utilize the latter method; therefore, the internal diameter of conduit 72 is made sufficiently small so that vapor bubbles cannot freely pass liquid therein, whereby the liquid is removed from trap 74 by lifting of liquid in conduit 72 by vapor lift action. As the liquid level in trap 74 lowers, liquid flows from trap 78 through conduit 80 into

trap 74. In this manner, the liquid is drained from trap 78 causing weak inert gas to by-pass the low temperature evaporator 13a and flow directly through conduit 76 into high temperature evaporator section 13b. Heating element 82 is so arranged relative to trap 74 that, if necessary, the last portion of liquid is removed from the bottom of the trap by vaporizing the liquid. When trap 74 is depleted of liquid, rectified refrigerant vapor flows from conduit 56 through conduits 72 and 34 into evaporator section 13a. The flow of refrigerant vapor directly into evaporator section 13a, together with the bypassing of inert gas around evaporator section 13a, greatly increases the partial pressure of refrigerant vapor in said section which causes the refrigerant vapor to condense therein and the heat of condensation rapidly melts the frost from the exterior of said section. The liquefied refrigerant accumulates in evaporator section 13a until it overflows the dams 26 at which time it flows through conduit 13c into high temperature evaporator section 13b. In the high temperature evaporator section, the liquid refrigerant vaporizes and diffuses into the inert gas flowing thereinto through by-pass conduit 76. In this manner, food storage compartment 22 continues to be refrigerated even though the low temperature evaporator is being defrosted. It is to be noted that the melting of frost from the low temperature section of the evaporator causes refrigerant vapor to be condensed therein, which liquefied refrigerant produces refrigeration in the high temperature section of the evaporator. In other words, the refrigerating effect of the frost on the low temperature section is used to produce refrigeration in the high temperature section.

The size and arrangement of conduit 34 and by-pass 76 is such that during a defrosting period sufficient inert gas is by-passed around the low temperature section of the evaporator to cause an appreciable increase in the partial pressure of refrigerant vapor in this section, resulting in condensation of refrigerant vapor therein, while at the same time this quantity of inert gas is not sufficient to reduce the partial pressure of refrigerant vapor in the high temperature evaporator section to the point that this latter section would become a freezing section. To insure that all the refrigerant vapor that is expelled from generator 10 during a defrosting period passes directly to the low temperature section of the evaporator, the trap 58 is provided at the inlet to condenser 12. When trap 74 is open, the liquid head in trap 58, through which the refrigerant vapor bubbles during normal operation, prevents the vapor from dividing between the evaporator and condenser.

Referring again to Fig. 2, the expandable diaphragm 138 of switch control 88 is so designed that upon increase in temperature of the low temperature evaporator 13a to the melting point of ice, the pressure therein increases sufficiently to expand the diaphragm to the point that the abutment 140 contacts and moves switch lever 141 to the left, thereby snapping switch button 142 to the left, whereby switch 142' is opened and heating element 82 (Fig. 1) is deenergized. As shown, thermal bulb 90 is arranged in heat exchange relation with the low temperature evaporator at a point some distance from the outlet end thereof. By this arrangement, the heating element 82 is deenergized before the entire low temperature evaporator is defrosted. However, for a short period after the heating element has

been deenergized, condensation of refrigerant vapor continues in the low temperature evaporator until trap 74 cools to a temperature that liquid refrigerant collects therein and stops the flow of refrigerant vapor to the evaporator, during which interval the remainder of the low temperature evaporator will have been defrosted. The heat capacity of heating element 82 and of the vapor lift pump portion of conduit 72 is low so that after the heating element has been deenergized, this assembly cools rapidly, causing refrigerant vapor to be condensed therein and fill trap 74. In order to expedite the filling of trap 74, conduit 72 may be cooled in any suitable manner, as by heat transfer fins (not shown). As refrigerant vapor condenses and fills traps 74, liquefied refrigerant flows therefrom through conduit 80 into trap 78, thereby closing by-pass 76 and causing all of the weak inert gas to flow through conduit 34 into the low temperature evaporator. Liquid refrigerant having been accumulated in the low temperature evaporator section during the defrosting period, refrigeration is resumed in this section immediately upon the closing of trap 78 in by-pass 76.

While I have illustrated and described but one specific embodiment of my invention, it obviously may take other forms and be variously applied within the scope of the following claims.

What is claimed is:

1. A refrigerating apparatus provided with a low temperature evaporator, a high temperature evaporator and means for supplying liquid refrigerant to said evaporators, a first control mechanism for controlling the supply of refrigerant to said evaporators responsive to the temperature of said high temperature evaporator, a second control mechanism for stopping the flow of liquid refrigerant to said low temperature evaporator and for flowing refrigerant vapor thereto while continuing the flow of liquid refrigerant to said high temperature evaporator, a common control knob for adjusting said first control mechanism and for energizing said second control mechanism, and a third control mechanism thermostatically operated responsive to a predetermined high temperature of said low temperature evaporator for deenergizing said second control mechanism.

2. An absorption refrigerating apparatus including a generator, a low temperature evaporator and a high temperature evaporator, a valve for controlling a supply of heat to said generator, a thermostat for actuating said valve to normally maintain the temperature of said high temperature evaporator substantially constant, a defrosting device for said low temperature evaporator, mechanism for manually energizing said defrosting device, means thermostatically operated responsive to the temperature of said low temperature evaporator for deenergizing said defrosting device, and a common actuating mechanism for adjusting the setting of the thermostat that actuates said valve and for manually energizing said defrosting device.

3. A unipressure absorption refrigerating system including a generator, a condenser, an evaporator, an absorber, conduits, including a defrosting device, interconnecting said elements and a control mechanism, said control mechanism including a thermostatically-operated valve for controlling a supply of heat to said generator, a switch for controlling a supply of heat to said defrosting device, said switch being arranged to be closed manually and opened automatically re-

5 sponsive to the temperature of said evaporator, and a common actuating member for adjusting said thermostatically-operated valve and for manually closing said switch.

4. A dual regulating and defrosting control for a unipressure absorption refrigerating system having a generator, a condenser, an evaporator, an absorber, conduits, including a defrosting device, interconnecting said elements to form a refrigerant circuit, an absorbent circuit and an inert gas circuit, said defrosting device including means for by-passing said condenser and flowing refrigerant vapor directly into said evaporator and for retarding flow of inert gas to said evaporator, said dual control including a thermostatically-operated mechanism for controlling a supply of heat to said generator, an element manually operated for energizing said defrosting device, and automatically operated for deenergizing said defrosting device, and a common adjusting member for adjusting said thermostatically-operated mechanism and for energizing said defrosting device.

5. A dual regulating and defrosting control for a unipressure absorption refrigerating system 25 having a generator, a condenser, an evaporator, an absorber and conduits interconnecting said elements to form a refrigerant circuit, an absorbent circuit, an inert gas circuit, and a plurality of defrosting circuits, said defrosting circuits including means for by-passing said condenser and flowing refrigerant vapor directly into said evaporator and for by-passing inert gas around said evaporator, said dual control including a thermostatically-operated valve for supplying heat to said generator in accordance with the temperature of said evaporator, an element manually energized for opening said defrosting circuits and automatically deenergized responsive to the temperature of said evaporator for closing said defrosting circuits, and a common remotely-operated adjustment for adjusting said thermostatically-operated valve and for manually energizing said element.

6. An absorption refrigerating system of the unipressure type including a generator, a rectifier, a condenser, an evaporator, an absorber and conduits connecting said elements to form a refrigerant circuit and an inert pressure-equalizing gas circuit, means for by-passing said condenser and for conveying refrigerant vapor from said rectifier into said evaporator, means in said inert pressure-equalizing gas circuit for by-passing at least a part of said evaporator, liquid traps in each of 50 said by-pass means for rendering said means ineffective, a gas burner for heating said generator, a thermostatic control operated responsive to the temperature of said evaporator for supplying gas to said burner, means including a heating element for removing liquid from said traps, a switch manually operated for energizing said heating element and thermostatically operated for deenergizing said heating element, and a single adjusting element for adjusting said thermostatic control and 55 for operating said switch.

7. An absorption refrigerating system of the unipressure type including a generator, a rectifier, a condenser, a low temperature evaporator, a high temperature evaporator, an absorber and conduits 60 connecting said elements to form a refrigerant circuit and an inert pressure-equalizing gas circuit, means for by-passing said condenser and for conveying refrigerant vapor from said rectifier into said low temperature evaporator, means in 65 said inert pressure-equalizing gas circuit for by-

passing said low temperature evaporator and for conveying inert pressure-equalizing gas directly into said high temperature evaporator, liquid traps in each of said by-pass means for rendering said means ineffective, a gas burner for heating said generator, a thermostatic control operated responsive to the temperature of said high temperature evaporator for supplying gas to said burner, means including a heating element for removing liquid from said traps, a switch which is manually closed for energizing said heating element and thermostatically opened responsive to the temperature of said low temperature evaporator for deenergizing said heating element, and a single adjusting element for adjusting said thermostatic control and for closing said switch.

8. In an absorption refrigerating system of the unipressure type, a generator, a condenser, an evaporator, an absorber, conduits interconnecting said elements to form a refrigerant circuit, additional conduits interconnecting said evaporator and said absorber to form an inert pressure-equalizing gas circuit, a defrosting device for said evaporator including a by-pass in said refrigerant circuit for conveying refrigerant vapor directly into said evaporator, a liquid trap in said by-pass, a second by-pass in said inert pressure-equalizing gas circuit for retarding the flow of inert pressure-equalizing gas to said evaporator, a liquid trap in said second by-pass and means interconnecting said by-passes for flow of liquid therebetween, means for heating said generator, a thermostatically-controlled valve operated responsive to the temperature of said evaporator for controlling the supply of heat to said generator, means for removing the liquid from said traps to render the traps ineffective and thereby initiate a defrosting cycle, said last-named means being manually started and automatically stopped responsive to the temperature of said evaporator, and a common control element for remotely adjusting said thermostatically-controlled valve and for manually initiating a defrosting cycle.

9. In an absorption refrigerating system of the unipressure type, a generator, a condenser, a low temperature evaporator, a high temperature evaporator, an absorber, conduits interconnecting said elements to form a refrigerant circuit, additional conduits interconnecting said evaporators and said absorber to form an inert pressure-equalizing gas circuit, a defrosting device for said low temperature evaporator including a by-pass in said refrigerant circuit for conveying refrigerant vapor directly into said low temperature evaporator, a liquid trap in said by-pass, a second by-pass in said inert pressure-equalizing gas circuit for retarding the flow of inert pressure-equalizing gas to said low temperature evaporator, a liquid trap in said second by-pass, means interconnecting said by-passes for flow of liquid therebetween, means for heating said generator, a thermostatically-controlled valve operated responsive to the temperature of said high temperature evaporator for controlling the supply of heat to said generator, means for removing the liquid from said traps to render the traps ineffective, said last-named means being manually started and automatically stopped responsive to the temperature of said low temperature evaporator, and a common control element for remotely adjusting said thermostatically-controlled valve and for manually initiating a defrosting cycle.

10. In a refrigerating system of the unipressure type, a generator, a condenser, a low tempera-

ture evaporator, a high temperature evaporator, an absorber, conduits interconnecting said elements to form a refrigerant circuit, additional conduits interconnecting said evaporators and said absorber to form an inert pressure-equalizing gas circuit, a defrosting device including a conduit connecting said generator and the low temperature evaporator for flow of refrigerant vapor therethrough, a liquid trap in said last-mentioned conduit for blocking flow of refrigerant vapor therethrough, a conduit in said inert pressure-equalizing gas circuit for by-passing the low temperature evaporator and for conveying inert pressure-equalizing gas directly into the high temperature evaporator, a liquid trap in said last-mentioned conduit for blocking flow of inert pressure-equalizing gas therethrough, a dual regulating and defrosting control, said dual control including a thermostatically-operated valve for controlling a supply of heat to said generator responsive to the temperature of said high temperature evaporator, a mechanism that is manually operated to initiate a defrosting cycle and thermostatically operated responsive to the temperature of the low temperature evaporator for interrupting said defrosting cycle, and a common control knob for adjusting said thermostatically-operated valve and for operating said mechanism to initiate a defrosting cycle.

11. In a refrigerator, a cabinet having a freezing compartment, a food storage compartment and an apparatus compartment, an absorption refrigerating apparatus including a low temperature evaporator in said freezing compartment, a high temperature evaporator in said food storage compartment connected to the low temperature evaporator for flow of refrigerant fluid from the low to the high temperature evaporator and a generator and control mechanism in said apparatus compartment, a defrosting device including means for increasing the vapor pressure of refrigerant vapor in the low temperature evaporator, for decreasing the vapor pressure of refrigerant vapor in the high temperature evaporator and for conveying refrigerant vapor into the low temperature evaporator which vapor is condensed therein and liquid refrigerant produced thereby flows into the high temperature evaporator to produce refrigeration therein, said control mechanism including a thermostatically-operated valve for supplying heat to said generator, a switch manually operated for energizing said defrosting device and thermostatically operated responsive to the temperature of said low temperature evaporator for deenergizing said defrosting device, and a common adjusting knob accessibly located in an upper part of said cabinet for adjusting the setting of said thermostatically-controlled valve and for energizing said defrosting device.

12. In a refrigerator, a cabinet having a freezing compartment, a food storage compartment and an apparatus compartment, an absorption refrigerating apparatus including a low temperature evaporator in said freezing compartment, a high temperature evaporator in said food storage compartment and a generator and control mechanism in said apparatus compartment, a defrosting device including means for conveying refrigerant vapor to said low temperature evaporator, means for increasing the vapor pressure of refrigerant vapor in said low temperature evaporator whereby the refrigerant vapor conveyed thereto is condensed therein and the latent heat of condensation is utilized to heat said low

13

temperature evaporator, means for conveying liquid refrigerant from the low temperature evaporator to the high temperature evaporator whereby refrigeration is produced by the high temperature evaporator during the defrosting of the low temperature evaporator, said control mechanism including a thermostatically-operated valve operable responsive to the temperature of said high temperature evaporator for supplying heat to said generator, a switch manually operated for energizing said defrosting device and thermostatically operated responsive to the temperature of said low temperature evaporator for deenergizing said defrosting device, and a common adjusting knob accessibly located in an upper part of said cabinet for adjusting the setting of said thermostatically-controlled valve and for energizing said defrosting device.

13. A defrosting control for a unipressure absorption refrigerating system having a generator, a condenser, an evaporator, an absorber and conduits, including a defrosting device, interconnecting said elements, said control including a thermostatically-operated valve for controlling a supply of heat to said generator, a mechanism for controlling a supply of heat to said defrosting device, said mechanism being arranged to be manually energized and automatically deenergized responsive to the temperature of said evaporator, a common actuating member for adjusting said thermostatically-operated valve and for manually energizing said mechanism, and a manually-operated device for deenergizing said mechanism.

14. In a refrigerating system of the unipressure type, a generator, a condenser, a low temperature evaporator, a high temperature evaporator, an absorber, conduits interconnecting said elements to form a refrigerant circuit, additional conduits interconnecting said evaporators and said absorber to form an inert pressure-equalizing gas circuit, a defrosting device including a conduit connecting said generator and the low temperature evaporator for flow of refrigerant vapor therethrough, a liquid trap in said last-mentioned conduit for blocking flow of a refrigerant vapor therethrough, a conduit in said inert pressure-equalizing gas circuit for by-passing the low temperature evaporator and for conveying inert pressure-equalizing gas directly into the high temperature evaporator, a liquid trap in said last-mentioned conduit for blocking flow of inert pressure-equalizing gas therethrough, a dual regulating and defrosting control, said dual control including a thermostatically-operated valve for controlling a supply of heat to said generator responsive to the temperature of said high temperature evaporator, a mechanism that is manually operated to initiate a defrosting cycle and thermostatically operated responsive to the temperature of the low temperature evaporator for

14

interrupting said defrosting cycle, a common control knob for adjusting said thermostatically-operated valve and for operating said mechanism to initiate a defrosting cycle, and a reset mechanism for manually interrupting a defrosting cycle.

15. In a refrigerator, a cabinet having a freezing compartment, a food storage compartment and an apparatus compartment, an absorption refrigerating apparatus including a low temperature evaporator in said freezing compartment, a high temperature evaporator in said food storage compartment and a generator and control mechanism in said apparatus compartment, a defrosting device including means for conveying refrigerant vapor into said low temperature evaporator wherein said vapor is condensed and the latent heat of condensation is utilized to heat said low temperature evaporator, and means for conveying liquid refrigerant from the low temperature evaporator to the high temperature evaporator whereby refrigeration is produced in said high temperature evaporator during the defrosting of said low temperature evaporator, said control mechanism including a thermostatically-operated valve for supplying heat to said generator, a switch manually operated for energizing said defrosting device and thermostatically operated responsive to the temperature of said low temperature evaporator for deenergizing said defrosting device, a common adjusting knob accessibly located in an upper part of said cabinet for adjusting the setting of said thermostatically-controlled valve and for energizing said defrosting device, and a reset mechanism for manually deenergizing said defrosting device.

16. Refrigeration apparatus including a cooling element, automatic control means comprising a first thermostat operative to maintain the temperature of said cooling element within a substantially constant value or range, means operative to cause the temperature of said cooling element to rise above said constant value or range, means operable to start said modifying means, automatic means comprising a second thermostat for stopping said modifying means upon a predetermined rise in a temperature condition affected by said cooling element, and manual means for stopping said modifying means independently of the operative condition of said automatic means.

SVEN W. E. ANDERSSON.
